CLAIM

The ornamental design for a display screen with icon, as shown and described.

DESCRIPTION

The sole FIGURE is a front view of a display screen with icon showing the new design.

The broken lines of uneven length show the display screen and form no part of the claimed design.

1 Claim, 1 Drawing Sheet

Related U.S. Application Data

abandoned, which is a continuation of application No. 29/717,990, filed on Dec. 20, 2019, now Pat. No. Des. 885,434, which is a continuation of application No. 29/643,565, filed on Apr. 10, 2018, now abandoned.
